UNITED STATES PATENT OFFICE.

ALBERT J. HART, OF CROMWELL, INDIANA.

TRACTION-ENGINE.

SPECIFICATION forming part of Letters Patent No. 417,419, dated December 17, 1889.

Application filed August 26, 1889. Serial No. 321,964. (No model.)

To all whom it may concern:

Be it known that I, ALBERT J. HART, of Cromwell, in the county of Noble and State of Indiana, have invented a new and Improved Traction-Engine, of which the following is a full, clear, and exact description.

The invention relates to traction-engines; and its object is to provide a suitable mechanism for balancing the machine, at the same time gearing the four independent wheels with each other.

The invention consists of certain parts and details and combinations of the same, as will be hereinafter fully described.

Reference is to be had to the accompanying drawings, forming a part of this specification, in which similar letters of reference indicate corresponding parts in all the figures.

Figure 1 is an inverted plan view of a traction-engine provided with the improvement. Fig. 2 is a sectional side elevation of the same on the line $x-x$ of Fig. 1. Fig. 3 is an enlarged transverse section of mechanism for connecting the front axles. Fig. 4 is a plan view of the same and adjacent parts, and Fig. 5 is a face view of the main gear-wheel and the connecting mechanism of the front axle.

The traction-engine A is provided with the usual boiler B, and the engine C, connected by its main driving-shaft D with a transversely-extending shaft E by a belt and pulleys or by sprocket-wheels and a chain, as is plainly shown in Fig. 1. The drive-shaft D imparts, by an intermediate mechanism, hereinafter more fully described, motion to the front wheels F and F' and the rear wheels G and G' of the traction-engine. The front wheels F and F' are secured on the outer ends of the shafts H and H', respectively, extending in line with each other, and mounted to turn on suitable bearings formed on the front axle-tree I, supported on the universal joint J. The joint J is formed by providing the axle-tree I at the top and bottom with trunnions J', on which is mounted to swing horizontally a frame J², provided on one side with a hub J³, journaled in a hanger B', secured to the under side of the boiler B. On the opposite side of the frame J², and in line with the hub J³, is formed a trunnion J⁴, mounted to turn in a hanger B², secured to

the under side of the front end of the boiler B. The frame J² is thus mounted to swing vertically, while the axle-tree I is mounted to swing horizontally underneath the front end of the boiler B.

At the adjoining inner ends of the axles H and H' is mounted to turn loosely a gear-wheel K, carrying in its web radial studs or shafts K², on which are mounted to turn the bevel gear-wheels K', preferably three in number, as shown in Fig. 5. (See, also, Fig. 3.) The gear-wheels K' mesh at opposite sides into the bevel gear-wheels H² and H³, secured on the axles H and H', respectively.

When the drive-wheels F and F' are in their normal position, as shown in Fig. 1, and motion is given to the gear-wheel K, the latter transmits its motion by the gear-wheels K' to the gear-wheels H² and H³ on the axles H and H', so that the latter are rotated simultaneously, turning the wheels F and F'. When the axle-tree I is shifted by the steering mechanism so that one of the wheels F or F' remains stationary for a short time, then the other wheel F' or F is still turned by the wheel K, as the bevel gear-wheels K' roll off on the gear-wheel H² or H³, the axle of the said wheel remaining stationary, while the gear-wheels K' drive the moving axle with increased speed. The mechanism above described, and shown in Figs. 3 and 5, thus permits of driving one of the front wheels F or F', while the other remains stationary or is turned backward.

The gear-wheel K meshes into a gear-wheel L, secured on a transverse shaft L', mounted to turn in suitable bearings formed in the brackets J⁵, extending from the frame J². On the shaft L' is secured a bevel gear-wheel L², which meshes into a bevel gear-wheel fastened on one end of a shaft N, mounted to turn in the hub J³ of the frame J², previously mentioned.

In line with the shaft N is a shaft N', abutting against the said shaft N, which latter is connected with the said shaft N' by a mechanism similar to the one shown in Fig. 3—that is, two bevel gear-wheels are secured at the adjoining ends of the shafts N and N', and mesh in a series of bevel gear-wheels arranged in the web of the gear-wheel O, similar to the gear-wheel K. (Shown in Fig. 3.)

The gear-wheel O meshes into a pinion O', secured on a longitudinally-extending short shaft O², mounted to turn in suitable bearings arranged in the hanger B³, which latter is secured to the under side of the boiler B and also forms a bearing for the shaft N'. On the shaft O² is secured a bevel gear-wheel O³, which meshes into a bevel gear-wheel O⁴, secured on the driving-shaft E. On the shaft N' is secured a gear-wheel N², which meshes into an intermediate gear-wheel N³, mounted to turn on the stud B⁴, projecting from the boiler B. The intermediate gear-wheel N³ meshes into a gear-wheel N⁴, secured on one end of a shaft N⁵, mounted to turn in suitable bearings on one side of the fire-box of the boiler B. On this shaft N⁵ is secured a bevel gear-wheel N⁶, meshing into a bevel gear-wheel N⁷, secured on a shaft N⁸, extending transversely and mounted to turn in suitable bearings on one side of the fire-box of the boiler B. On the shaft N⁸ is secured a pinion N⁹, which meshes into a gear-wheel P, similar in construction to the gear-wheels K and O, previously described, and provided in its web with a series of bevel gear-wheels meshing at opposite sides into gear-wheels secured on the axles Q and Q', arranged in line with each other and carrying the rear wheels G and G'.

The axle-tree I is pivotally connected at opposite sides of its fulcrum with the rods R R, connected with each other by a chain R', passing over the steering-pulley S, secured on the usual steering-shaft T, arranged on the rear end of the boiler B and carrying a hand-wheel U for conveniently turning the steering-wheel S to change the position of the axle-tree I, and consequently the position of the wheels F and F', in order to turn around a curve.

The teeth of the gear-wheel K are somewhat rounded off, so that when the position of the axle-tree I is changed by the steering apparatus said gear-wheel K does not get out of mesh with the gear-wheel L, as is plainly shown in Fig. 4.

The operation is as follows: When the engine C is set in motion, its shaft D imparts a rotary motion to the driving-shaft E, which, by its connection with the shaft O², turns the pinion O', turning the gear-wheel O, which latter, by its bevel gear-wheels, rotates the shafts N and N', respectively. The shaft N imparts a rotary motion to the shaft L' and the gear-wheel L, so that the latter turns the gear-wheel K, which imparts a rotary motion to the axles H and H', as previously described. The shaft N transmits its rotary motion by the gear-wheels N², N³, and N⁴ to the shaft N⁵, which turns the shaft N⁸, carrying the gear-wheel N⁹, and the latter turns the gear-wheel P, turning the axles Q and Q', supporting the rear wheels G and G'. The wheel P transmits its motion to the two axles Q and Q' as long as there is no undue friction on the wheels G and G'; but in case one of the latter meets with an obstruction it may remain sta-

tionary, while the other is still turned by the gear-wheel P in the same manner as previously described in reference to the front wheels F and F'. In the same manner the gear-wheel O may transmit motion only to the shaft N, while the other shaft N' remains stationary, and vice versa. This arrangement permits of turning the four wheels F F' and G G' forward at the same time, but it also permits any one of the wheels to remain stationary while the other is turning, or even to move backward while the others turn forward.

It is understood that as the front axles II and II' are mounted to turn in the axle-tree I, which is a universal joint, all undue strain is taken off of the front wheels in case they travel over uneven ground. Thus it will be seen that all the wheels run independently of each other, and the wheel which has the farthest distance to go in turning pulls with the same power as the wheel that has to travel the shortest distance.

As the weight of the traction-engine is equally distributed on all four wheels, the machine will go easily over soft mud and through sand, and it will turn around in the same very easily.

It will be understood that the herein-described driving mechanism and running-gear may be applied to other machines or vehicles than traction-engines.

Having thus fully described my invention, I claim as new and desire to secure by Letters Patent—

1. The combination, with the vertical longitudinally-extending frame J², having a trunnion J⁴ at its front end, a hub J³, and inwardly-extending brackets J⁵ at its rear end, and the bearings B' B³ in which said hub and trunnion rock, of the axle-tree I, passed transversely through the frame and connected at its upper and lower sides therewith by vertical pivots J' J', the axles II H', mounted in bearings between the upper and lower sides of the axle-tree at the front thereof and connected by the compensating gear K, the transverse shaft L', mounted in said brackets and provided with a pinion L, meshing into gear K and a bevel-gear L², and the driving-shaft N, extending through the hub J, and provided with a bevel-gear L³, meshing into bevel-gear L², substantially as set forth.

2. In a traction-engine, the combination, with a drive-shaft, of two shafts operated from the said drive-shaft and placed in line with each other, two independent front axles operated from one of the said two shafts, and two independent rear axles operated by the other of the said two shafts, substantially as shown and described.

3. In a traction-engine, the combination, with a drive-shaft, of two shafts operated from the said drive-shaft and placed in line with each other, two independent front axles operated from one of the said two shafts, two independent rear axles operated by the other

of the said two shafts, and an axle-tree on which the said front axles are mounted to turn, substantially as shown and described.

4. In a traction-engine, the combination, 5 with a drive-shaft, of two shafts operated from the said drive-shaft and placed in line with each other, two independent front axles operated from one of the said two shafts, two independent rear axles operated by the other of the said two shafts, an axle-tree on which the said front axles are mounted, and a universal joint for connecting the said axle-tree with the front end of the boiler, substantially as shown and described.
- 10 5. In a traction-engine, the combination, 15

with a drive-shaft, of two shafts operated from the said drive-shaft and placed in line with each other, two independent front axles operated from one of the said two shafts, two independent rear axles operated by the other of the said two shafts, an axle-tree on which the said front axles are mounted, a universal joint for connecting the said axle-tree with the front end of the boiler, and a steering apparatus connected with the said axle-tree, 20 substantially as shown and described.
